Attest

Attest, Jan. 21, 1873.

UNITED STATES PATENT OFFICE.

HENRY A. WOOD, OF BANGOR, MAINE.

DESIGN FOR A COOKING-STOVE.

Specification forming part of Design No. 6,377, dated January 28, 1873.

To all whom it may concern:

Be it known that I, HENRY A. WOOD, of Bangor, in the county of Penobscot and State of Maine, have invented a Design for Stoves, of which the following is a specification:

The nature of my design is fully represented in the accompanying photographic illustration, to which reference is made.

The body of the stove has a smooth finish, as illustrated. The stove, around the base, is ornamented with a molding of the pattern shown, and the sides and front, around the top, flare outwardly in the manner and form shown. The doors are molded around the edges, and

have also inside of the molding a bead and border. In the center is placed the monogram "W. B. & Co.," all of which is fully illustrated in the photograph forming a part of this specification, to which reference is made.

What I claim as my invention, and desire to secure by Letters Patent, is—

The design for a stove, as herein described and shown in the accompanying photograph, either with or without the monogram.

HENRY A. WOOD.
